(57) **CLAIM**

The ornamental design for a view of the portable toilet, showing my new design as shown and described.

DESCRIPTION

FIG. 1 is a front elevation view of a portable toilet showing my new design;

FIG. 2 is a front plan view of a portable toilet showing my new design;

FIG. 3 is a side view of a portable toilet showing my new design;

FIG. 4 is a rear plan view of the portable toilet showing my new design;

FIG. 5 is a top view of the portable toilet shelf showing my new design; and,

FIG. 6 is a bottom view of the portable toilet showing my new design.

In the drawings, the broken lines depict environmental subject matter only and form no part of the claimed design.
